UNITED STATES PATENT OFFICE

SPENCER W. MCKELLIP, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA

FLEXIBLE HINGE RING

Application filed January 7, 1932. Serial No. 585,372.

This invention relates to supporting "hinge" rings for sound reproducing diaphragms, such, for example, as the diaphragms of sound reproducers of radio receivers. The general object of the invention is to provide a novel supporting ring having the desirable characteristics set forth fully hereinafter and which is especially adapted for supporting the conical diaphragm of the electrodynamic reproducer of a modern radio receiver.

A more specific object of the invention is to provide an inexpensive mounting or supporting ring for resiliently attaching a conical diaphragm to the diaphragm housing.

Another object of the invention is to provide a diaphragm supporting ring which readily enables a change in the frequency response characteristics of the diaphragm without changing the other elements of the reproducer. As pointed out hereinafter, the natural or resonant frequency of the reproducer may be varied by simply varying the construction of the supporting ring as to its constituent materials and their properties.

A further object of the invention is to provide a sound reproducer wherein the largest effective sound radiating area is obtained with a given diaphragm frame size and a minimum size hinge ring coupling to obtain the greatest degree of flexibility where so desired.

A still further object of the invention is to provide a supporting ring adapted for action which, in combination with the inherent resiliency of the ring, enables the proper flexing thereof without materially straining the fibres of the material of which the ring is composed.

Another object of the invention is to provide a supporting ring which will maintain the conical diaphragm in its true round shape but which has sufficient resiliency to allow the diaphragm to function normally without producing audible buzzes.

Another object of the invention is to provide a supporting ring which, due to its inherent uniformity, will hold the diaphragm in a uniform position and allow it to move in and out in a parallel plane in the air gap,

thereby eliminating the possibility of seesaw action, which naturally would result in buzzes due to the voice coil rubbing in the air gap possibly at both extreme ends of its vibratory motion particularly on the lower frequencies at high amplitudes.

Other objects and characteristics of the invention will be clearly apparent from the following detailed description and the accompanying drawing in which

Fig. 1 illustrates the preferred form of the supporting ring in section; and

Figs. 2 and 3 are similar sectional views showing the modified forms of the ring.

As illustrated in Fig. 1 of the drawing, the ring is provided with suitable corrugations, which general construction is, of course, common and well known in the sound reproducer art. I prefer, however, to construct the ring as clearly illustrated in the preferred embodiment of Fig. 1, wherein the flat annular portion 1 serves to firmly attach the ring to the diaphragm housing. Portion 2 is the corrugated part of the ring and conical portion 3 serves to attach the diaphragm to the ring. The ring may be attached to the diaphragm housing and the diaphragm may be attached to the ring in any suitable manner, such as by any of the methods commonly employed in sound reproducers. I have found that the supporting ring gives best results if the corrugations thereof are uniformly and continuously curved and if the maximum depth of the corrugations equals approximately one-half the maximum width thereof.

While I prefer the design illustrated in Fig. 1, the ring is not limited to any particular number of corrugations. In the preferred form of Fig. 1, two corrugations are provided and the construction may be for convenience referred to as a "double corrugation". In Fig. 2, there is illustrated a form of ring in which a single corrugation is used, while in Fig. 3, three corrugations are provided. For convenience, these forms may be referred to as single and triple corrugations respectively. I prefer the form of Fig. 1 because it appears to be the most practical in most instances, although the form of Fig. 2 may be used where extremely high rigidity

is desired and the form of Fig. 3, may be used where extremely high flexibility is desired.

In accordance with the invention, the supporting ring which may take any of the designs illustrated or any other suitable design, is formed of rubberized paper, preferably alpha pulp fibre paper impregnated with rubber. This is advantageously accomplished by employing latex and precipitating the rubber particles upon the fibres during the manufacture of the paper or by the precipitation of the rubber particles on a sheet of paper passed through latex. The precipitation of the rubber particles upon the latex in either case is accomplished according to well known methods. Although the invention contemplates broadly the use of rubberized paper, the preferred materials have been found thus far to give the best results. The rubberized paper, however, may be formed by passing a sheet of paper through rubber dissolved in a suitable solvent (a rubber cement) or by treating the paper sheet with a water dispersion of rubber. The percentage of rubber to paper fibres in the rubberized paper product may vary widely, depending upon the exact properties desired in the supporting ring. For example, if the paper is made from paper stock impregnated with precipitated latex during the manufacture of the paper, the product may contain 20% of rubber. In the method where the finished paper is impregnated with the latex solution and the rubber particles precipitated therefrom, a product containing up to 50% rubber may be used. In the case of the impregnation of the paper with rubber cements and the like 15% of rubber in the product has been found to give satisfactory results. In the preferred method, the latex is added to the beater after the paper fibres have been subjected to the beating operation. The rubber particles in the latex are precipitated upon the fibres according to the usual practices and the paper is thereafter formed on a paper machine or in any other suitable manner as is commonly employed in the paper industry. When properly processed and treated, the rubber impregnated paper contemplated herein will be found to be especially strong and resilient, which characteristics are absolutely essential not only to the successful making of the ring in accordance with the method set forth hereinafter, but also to successful functioning of the ring when incorporated in a sound reproducer. It will be understood, of course, that rubberized paper of the type contemplated may have proper anti-oxidents or age-rights incorporated at the time of impregnating, in order that maximum life characteristics may be obtained.

By properly proportioning the thickness of the stock used and varying the physical

properties of the stock accordingly, almost any desired results as regards frequency response, flexibility, rigidity, etc. can be obtained in the finished ring without varying the dimensions of the ring. By varying the physical properties of the stock, I mean varying the raw components used therein. Thus, the characteristics of the completed ring will depend upon the particular pulp utilized, the treatment of the pulp, the density of the sheets, the type of sizing, the absorbency of the finished stock, etc. The type of rubber used, the concentration of the impregnating solution, the method of impregnating, and other variable factors relating to the impregnating material and method will also determine the characteristics of the ring. Likewise, the process to which the finished stock is subjected will affect the characteristics. By suitably varying these various factors in relation to each other, the ring may be given any desired frequency response characteristic resulting from variations in its mechanical structure.

The mechanical structure and design of the supporting ring having been described, the process of making the same will now be set forth. This process involves the ordinary embossing process which is used generally in imparting desired shapes to paper sheet material, I have found, however, that to successfully emboss a ring of the type used herein into a permanent shape, the following procedure is practically necessary. A pair of dies are first formed in the following manner:—A plate of hard metal, which may be about one-half inch in thickness, is machined to the shape which it is desired to impart to the ring. From this plate, a second soft plate is formed by providing a dam around the edge of the hard plate and pouring or molding the soft plate from soft metals such as lead-antimony of various percentage or Babbitt metal. The hard and soft plates are then placed in a hydraulic or similar press of sufficient tonnage to press the soft plate firmly against the hard plate and thus impart to the soft plate the exact contour of the hard plate. We now have the necessary dies with which to carry out the embossing process.

The most desirable type of press for embossing the ring of the present invention is a Sheridan cam type embossing press either of the steam or electrically heated type. Such press should, of course, be of suitable tonnage, the tonnage depending upon the size and number of dies to be mounted at one time in the press. Other types of presses, such, for example, as quick-acting heated hydraulic presses may be used. Heating is required to soften the rubber and fibres to enable the proper embossing by allowing the stock to give or stretch. When it is possible to emboss a ring that is already cut or died out to its finished dimensions, I have found

that the best results may be obtained by embossing the ring from a solid piece of stock with a uniform pressure across the die.

The heat of the press should be maintained as low as is possible to obtain a smooth even embossing and to keep the usual characteristics of the paper. In the case of latex impregnated paper, a temperature of from 140° to 160° F. is desirable. The pressure applied should be sufficient to squeeze the stock down permanently from 60% to 50% of its original thickness. It is necessary that the pressure be applied uniformly across the dies as a finished uniform thickness must be had if the completed ring is to maintain its shape and not warp or buckle. I have found that an initial thickness of .010 to .040 of an inch giving a finished ring of .005 to .020 of an inch in the thickness is very satisfactory, although these values are not to be taken as limiting the thickness of the ring to the range specified.

After a plurality of rings have been embossed as described above, they may be cut or died out singly or in groups. A very satisfactory method is to punch out a single hole in each of the embossed pieces by means of a suitable die preferably at the time of the embossing. The embossed pieces may then be nested on a suitable pin. A number of embossed pieces can be cut at one time, depending upon the thickness of the material. In some cases, it may be possible and practical to emboss and cut a number of concentric rings of different size from the same piece of material.

While I am fully aware that cone diaphragms of sound reproducers have heretofore been formed with corrugated edges, such prior art devices have been impractical from the standpoint of manufacture thereof. The improved ring of the present invention readily lends itself to a simple and practical process of manufacture and at the same time has the highly desirable characteristics pointed out above. It is to be understood, of course, that the invention is not to be limited to the specific disclosure set forth herein which is for the purpose of illustration only. Only such limitations as are imposed in the appended claims are to be placed upon the invention.

I claim:-

1. A corrugated supporting ring for sound reproducing diaphragms composed of rubberized paper.
2. A corrugated supporting ring for sound reproducing diaphragms composed of rubber-impregnated paper.
3. A corrugated supporting ring for sound reproducing diaphragms composed of alpha pulp paper impregnated with precipitated latex.
4. A method of making a corrugated supporting ring for a sound reproducing dia-

phragm, which comprises embossing a ring formed of rubberized paper.

5. A method of making a corrugated supporting ring for a sound reproducing diaphragm, which comprises treating paper with rubber in desired proportions to form stock, and embossing the stock to form the ring. 70

6. A method of making a corrugated supporting ring for a sound reproducing diaphragm, which comprises treating paper with rubber in desired proportions to form stock, forming a hard die member to the desired shape of the ring, forming a second die member from relatively soft material by 80 pressing it against the hard member, and embossing the ring in said die members.

7. A method of making a corrugated supporting ring for a sound reproducing diaphragm, which comprises treating paper with rubber in desired proportions to form stock, forming a hard die member to the desired shape of the ring, providing a dam around the edge of said member, molding relatively soft material on said hard member to form a second die member, and embossing the ring in said die members. 90
